COMBINATION BABY AND PARCEL CARRIER

William H. Head, Venice, Calif.

Application November 14, 1938, Serial No. 240,314

6 Claims. (Cl. 280—47)

My invention relates more particularly to a combination baby carrier, on wheels, which can be readily converted into a parcel or package carrier, the body or basket part thereof being converted from an open front baby holder, to a closed front barrel-like container to receive packages for its full length.

Among the salient objects of my invention are: To provide such an article having a body with open front and a seat to receive a baby therein in the usual manner with its little feet out in front on a suitable foot-rest, but having a plural member seat folded together which can be raised to close the front of the body and thus form a package receiving container for its full length, when the baby is removed from the carrier.

To provide a carrier of the character referred to in which a folding seat is provided, which when folded to seat position, occupies a position above the bottom of the body, thus providing a package-receiving space under the seat, with closure therefor, so that articles can be placed therein even while baby is seated in the carrier.

To provide a device of the character referred to which has a foldable support at its rear adapted to be let down to a position which will support the body in an inclined position, as when the baby may be asleep.

Other objects and advantages of my invention will appear from the following more detailed description of one practical embodiment thereof, taken with the accompanying drawings illustrating the same.

In order to fully explain my invention, I have illustrated it on the accompanying two sheets of drawings, which I will now describe:

Figure 1 is a front elevation of a carrier embodying my invention, showing the seat members opened up to form a front wall for the body or basket;

Figure 2 is a rear elevation thereof;

Figure 3 is a cross sectional view taken on line 3—3 of Fig. 1;

Figure 4 is a sectional view showing the foot rest, taken on line 4—4, of Fig. 1;

Figure 5 is a vertical sectional view taken on line 5—5 of Fig. 1;

Figure 6 is an enlarged detailed view of a foldable brace;

Figure 7 is a sectional view on line 7—7 of Fig. 6, showing details of construction; and

Figure 8 is a fragmentary side elevation showing the carrier in tilted position, with parts in section to show the plural seat members in folded position.

Referring now in detail to the embodiment of my invention as illustrated on the drawings, the body or basket 10, may be of any suitable or desired construction, but is shown of woven reeds or basket work, of barrel-like form, having its front side open with post members, 11, 11, forming the edges of the opposite sides, and with a cross rod 12 secured thereto. At the back is an elongated U-shaped member 13, forming an arched handle 13' whose sides extend to the bottom of the body, 10, which is provided with a floor 14, the front of which extends, in its middle portion, outwardly and is provided with two spaced short legs, as 15, 15, while at the rear of said floor is an axle rod 16, provided at its outer ends with two carrier wheels, 17, 17. Thus with the two wheels at opposite sides at the rear, and the two short legs at the front, said carrier will stand upright, in the manner illustrated.

Hingedly connected to the front part of said body, at the top of a lower closed member 18, is a seat member 19, to the rear edge of which is hingedly connected another seat board 20, so that said seat members fold together or collapse, as indicated clearly in Fig. 8, the rear edge of which is supported on two brackets, as 21, whereby said seat members are supported in position to be used as a seat, above the bottom floor 14, providing a space under said seat to receive packages and access to which is had at the rear, where door 22 is hinged at one side as at 23, and held by a clasp 24, at the other side, making it convenient to place and remove small parcels even while baby is seated in the carrier.

In the front of the solid front member 18 is a foot rest in the form of a cross rod bent rearwardly and thence downwardly through two eyelets 25, 25, and having its lower ends bent to short angles to be inserted in holes 26, 26 in said solid front member 18, so that it can be adjusted up and down to suit the convenience of the child. Said foot rest as a whole is designated 27.

Pivots connected to the back is an adjustable brace support for supporting the carrier in a backwardly inclined position, as indicated in Fig. 8. This is shown as composed of two U-shaped members 28 and 29. Member 28 is pivotally connected to the sides of the handle member, designated 13, as at 28', while the member 29, which is longer, is pivotally connected, as at 29', whereby they can be folded up close to the back, as seen in Fig. 5, or let down, as indicated in Fig. 8. Said short member 28 is provided at its cross portion with a rod 30, the opposite ends of which overlie the edges of the member 29, which is pro-

vided in its upper edge with holding notches, as 29', 29', clearly shown in Fig. 8.

In order to hold the operating end of the member 28 and the cross rod 30 in sliding connection with the opposite sides of the member 29, a guard clip or member 31 is provided at each end of said rod 30, and looped over the top edge and under the bottom edge of said member 29, as will be clear from Fig. 7.

- 10 As one means of holding said folding brace in its up position, I provide two spring clips, as 32, at opposite sides of the short member 28, adapted, when said brace is in its up position to yieldingly engage the two side members 13, 13, as 15 clearly seen in Figs. 5, 6 and 7.

When it is desired to use the carrier wholly as a carrier for packages, the seat members 19 and 20 are opened up, as indicated in Figs. 1 and 5, and held in place by the hook-and-eye means 20'.

- 20 It will be understood, of course, that while I have shown and described in detail one practical embodiment of my invention, that there are many changes in the details of construction and arrangement which can be made without departing 25 from the spirit of the invention, and I do not, therefore, limit my invention to the details and arrangements shown, except as I may be limited by the hereto appended claims.

I claim:

- 30 1. An article of the character shown and described including a barrel-like body having an open front and a closed bottom, and means therein for supporting a seat above said bottom with its front edge hinged in said open front, a seat 35 composed of two sections hinged together at the back and adapted to be opened up to a vertical position to form a closing wall for the open front of said body, whereby to convert it into a package carrier, open to its bottom, and 40 a handle for handling said carrier.

2. An article of the character shown and described including a barrel-like body having an open front and means therein for supporting a seat with its edge in said open front, a seat 45 composed of two hinged sections adapted to fold together flatwise on said supporting means, said seat being adapted to be opened up to form the front wall for the open front of said body, wheels for said carrier, a handle extended above the body, and a foldable supporting brace at the rear for supporting said body in a rearwardly inclined position, for the purpose described.

3. A combination baby and parcel carrier comprising a barrel-like body having a closed bottom 50 and an open front, a U-shaped handle member the sides of which are in the back wall of said body with the arched portion extended above the top of said body at the back, two seat members

hinged together at the back, with the front edge of the lower member hingedly connected in the open front, above the bottom, and adapted to be raised to a vertical plane to form a wall for said open front, means for securing said seat members in their wall-forming position, a door in the rear wall, between the side members of the handle member to give access to the bottom of said body, under the seat when said seat members are folded down to horizontal position, carrier wheels and supporting feet at the bottom of said body to support it in vertical upright position.

4. A combination baby and parcel carrier including a barrel-like body having a bottom, a seat supported therein above the bottom to provide a storage space under the seat, said barrel-like body being open in front down to the seat level, an opening through the body wall below the seat, with closure, to said storage space, said seat being adapted to be raised to close the open front of said body and open the storage space below said seat into the main body to convert said carrier into a parcel carrier, and wheels for supporting and moving said carrier.

5. A combination baby and parcel carrier consisting of a barrel-like body having a closed bottom and a seat supported therein above said bottom to provide a storage space thereunder, a door and opening through the bottom wall into said storage space, the front of said body being open above the seat level to receive a baby therein upon said seat, said seat being adjustable to close said open front and uncover said storage space, whereby to convert said carrier into a parcel carrier, carrier wheels thereunder, and a loop handle extended above said body to be placed over the shoulder of a person for carrying said carrier on the shoulder.

6. A combination baby and parcel carrier, convertible from one to the other, and consisting of a barrel-like body having a bottom and having a seat supported therein above the bottom to provide storage space under said seat, a door in the wall of said body below the seat to afford access to said storage space, said seat being in two parts and movable to a vertical plane, said barrel-like body being open in front above said seat, and adapted to be closed by said seat parts to convert said baby carrier into a parcel carrier open to the bottom thereof, carrier wheels for said carrier, and a loop handle extended upwardly in the plane of the back of said body and above said body, whereby to be placed over the shoulder of a person for carrying said carrier conveniently.

WILLIAM H. HEAD.
